Primary Examiner — Kevin K Rudzinski*Assistant Examiner* — Paul D Bohannon(74) *Attorney, Agent, or Firm* — Fredrikson & Byron, P.A.(57) **CLAIM**

I claim the ornamental design for a media stand, as shown and described.

DESCRIPTION

FIG. 1 is a front perspective view of a media stand of Applicant's design;

FIG. 2 is a front elevational view thereof;

FIG. 3 is a rear elevational view thereof;

FIG. 4 is a first side elevational view thereof, the second side elevational view opposite the first side elevational view and being a mirror image thereof;

FIG. 5 is a top plan view thereof;

FIG. 6 is a bottom plan view thereof;

FIG. 7 is a an enlarged view of the portion identified in FIG. 1 showing an enlarged perspective view of one of the three holes of the media stand, the other two holes being identical to the one of the three holes; and,

FIG. 8 is a sectional view taken along line 8-8 in FIG. 2, which runs through two of the three holes of the media stand, each hole being symmetric about the line 8-8 such that the cross-section of each hole opposite line 8-8 is a mirror image of the cross-section of each hole shown in FIG. 8.

Where included, broken lines showing environment or structure are for illustrative purposes only and form no part of the claimed design.
